UNITED STATES PATENT OFFICE.

KARL HEINRICH WOLMAN, OF BERLIN-GRUNEWALD, FRITZ PETERS, OF BERLIN, AND
HANS PFLUG, OF BERLIN-STEGLITZ, GERMANY.

WOOD PRESERVATIVE.

No Drawing. Application filed January 30, 1926, Serial No. 85,017, and in Germany January 2, 1926.

The object of the invention is a preservative for protecting wood from the attack of destructive fungi and animal pests. It has been found that an extremely effective agent against the attack of fungi as well as against the attack of animal organisms is obtained, if complex salts of tartaric acid with arsenic and an organic base are dissolved in suitable oils of mineral origin. Such complex salts 10 are for instance aniline arsenic tartrate ($C_4H_3O_4As.C_6H_5NH_2$), pyridine arsenic tartrate ($C_4H_3O_4As.C_5H_5N$), quinoline arsenic tartrate ($C_4H_3O_4As.C_9H_7N$), strychnine arsenic tartrate ($C_{21}H_{22}N_2O_2.C_6H_3O_6As.H_2O$) 15 etc.

In order to dissolve these compounds use can be made of the most varied oils of mineral origin. Such oils are for instance, suitable fractions of mineral oils, as well as oils 20 from coal-tar, brown-coal tar, wood tar, shale tar or low-temperature tars or also mixtures of these oils with one another. The oils employed must preferably be as little volatile as possible and be difficult to wash 25 out of the wood. Moreover they must have a good capacity of dissolving the said compounds. It is of course advantageous for the oils employed to be in themselves effective agents against destructive fungi or animal pests. For this reason it is desirable to 30 use coal tar oils or wood tar oils or other oils which are in themselves effective, or mixtures of the same with other oils.

Other compounds or substances may be 35 added to the described preservatives. For instance suitable organic compounds, such as phenols, naphthols or also organic bases can be dissolved in the oils, which are employed as solvents for the mentioned complex salts 40 of tartaric acid. Moreover other suitable compounds may be dissolved in these oils also before the dissolving of the complex

salts of tartaric acid, under the condition that they do not produce any precipitates with the said complex salts. Such compounds are for instance copper oleate, copper naphthenate, lead oleate, mercury oleate. Similarly these additions may be made to the prepared solutions of complex salts of tartaric acid in the oils. Other suitable oils of mineral, vegetable or animal origin may be added to the oils used for dissolving the arsenic compounds before or after the preparation of the solutions.

The oily preservatives composed in the manner described may be used for impregnating the wood in any suitable manner, for instance according to the full-cell process or according to an empty-cell process, for example the Ruping process or according to any other suitable treatment, such as steeping, coating, spraying and the like. The impregnating agents are extremely strong poisons for the organisms in question and are also characterized by the permanency of their action. This is owing to their slight volatility and to the difficulty in washing out the dissolved substances by water, so that the preservatives are excellently adapted also for protecting wood against pests living in water.

What we claim is:—

1. A preservative for wood, consisting of an oil of mineral origin and of a complex salt of tartaric acid with arsenic and an organic base dissolved in it.

2. A preservative for woods claimed in claim 1, and in which the said complex salt consists of quinoline arsenic tartrate.

In testimony whereof we affix our signatures.

KARL HEINRICH WOLMAN.
FRITZ PETERS.
HANS PFLUG.
